UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

COMPRESSOR.

1,401,603.

Specification of Letters Patent. Patented Dec. 27, 1921.

Application filed May 29, 1916, Serial No. 100,638. Renewed October 5, 1921. Serial No. 505,611.

To all whom it may concern:

Be it known that I, FRED D. HOLDSWORTH, a citizen of the United States, residing at Claremont, in the county of Sullivan and 5 State of New Hampshire, have invented certain new and useful Improvements in Compressors, of which the following is a full, clear, and exact specification.

My invention relates to compressors.

10 It has for its object to drive a plurality of compressors in an improved manner. A more specific object of my invention is to produce an improved arrangement of compressors and driving means therefor whereby 15 the maximum torque requirements are rendered so low and uniform that the compressors may be driven with the minimum of wear and tear on the driving and driven elements and the minimum of vibration, at 20 the same time that a very inexpensive, delicately controlled and compact installation is made possible. These and other objects of my invention will hereinafter appear.

In the accompanying drawings, I have for 25 purposes of illustration shown one embodiment which my invention may assume in practice.

In these drawings,—

Figure 1 is a plan view of a plurality of 30 compressors driven in accordance with this embodiment of my invention.

Fig. 2 is a side elevation of the installation shown in Fig. 1, the cylinders of the adjacent compressor being broken away to show the 35 positions of the pistons.

Fig. 3 is a diagram showing the relative positions of the several pistons in their several cylinders.

Fig. 4 is a series of diagrams showing 40 graphically, respectively, the crank effort for a single compressor due to the high and low pressure compressor units separately, the crank effort due to the combined effects of the high and low pressure units of a single 45 compressor, and the combined effects of twin compound compressors with one arrangement of cranks falling within my invention.

In these drawings I have illustrated a plurality of angle compound compressors 1 and 50 2, one being a right-hand while the other is a left-hand machine, and the two machines being disposed side by side.

As in a well known construction, each of these compressors is provided with a

vertical cylinder 3 and a horizontal cylinder 4, these cylinders having pistons 5 and 6, respectively. As usual, the cylinders of each machine are also connected through suitable pipe connections 7 and 8 with an intercooler 9, each machine of course being 60 also provided with a suitable inlet 10 and an outlet 11. It will also be noted that the pistons 5 and 6 of each compressor are also connected in the usual manner through suitable connecting rods 12 to a single crank 65 pin 13 carried on a horizontal shaft 14.

In my improved construction, the crank pin 13 of one compressor, as, for instance, the compressor 1, is offset with respect to the corresponding crank pin of the compressor 2, in such a manner that when the two compressors are simultaneously turned over through a complete cycle of operation, as when driven by any suitable source of power, the compressors are themselves operated in out of phase, herein split phase, 70 relation and as a result, instead of doubling the maximum and minimum instantaneous crank effort values and so doubling the range between the maximum and minimum values 75 for a single compressor, there is a considerable smoothing out of the combined crank effort curve and a resultant large increase in smoothness of operation, and a decrease in torque variation not only over what would 80 occur were the crank pins connected in axial alinement, but even over the results of a single compound compressor.

It will be understood that I have shown herein the 85 graph resulting from a 45° offsetting of the cranks, but that other angles of offset may be employed within the scope of my invention. With respect to the offsetting of the 90 cranks, but that other angles of offset may be employed within the scope of my invention. With respect to the offsetting of the cranks, but that other angles of offset may be employed within the scope of my invention. With respect to the offsetting of the cranks, but that other angles of offset may be employed within the scope of my invention. For instance, in using certain compressors 95 having different stage pressure ranges, weights of reciprocating masses, etc., it is 100 found desirable to offset the cranks by as much as 180°, it being understood that in the use of my invention such an angle is chosen as to give the desired smoothness of operation in each particular case, my invention 105 in no wise being limited to any particular angle of offset and the angle of 45° being shown only for purposes of illustration.

The compressors 1 and 2 may obviously be connected by various means so that the same may be operated in out of step relation to produce my improved results. In a preferred form, however, a single shafting is connected between the compressors. As shown herein, this shafting is also sectional, the compressor shafts 14 being relatively short and connected by couplings 15 of well known form, with an intermediate shaft 16, preferably co-axially disposed. This shafting may also be driven by any suitable means, although it will be evident that when the parts are operatively connected as described the compressors will operate as desired irrespective of the element directly receiving the motive force. In a preferred form, however, the shaft 16 forms the armature shaft of a motor 17 and is mounted in bearings 18 located on opposite sides of the motor.

While the compressors may be driven by motors of different types, in the embodiment of my invention illustrated herein, I have shown the same as driven by a synchronous motor which is itself excited by a small direct current generator 19 connected through a belt 20 with a pulley 21 preferably encircling one of the couplings 15 and connected thereto. It will also be noted that the bearings 18 for the armature shaft are spaced apart by such a distance that, when desired, the field magnets 22 of the motor may be adjusted longitudinally of the shaft to permit access to be had to the armature, the motor field structure for this purpose being mounted on suitable slides 23, well known in the motor art.

Attention is also directed to the fact that, while unloading mechanism of different forms may be used if desired, in the embodiment of my invention illustrated herein I have shown each compressor provided with a separate unloader valve 24, which may be of any well known type. By my improved construction and the use of these valves, I am enabled to load or unload one compressor at a different time from the other, as, for instance, by setting one valve to operate at a different pressure from the other, and am thereby able to obtain greater flexibility of control. For instance, in practice I have found that if one unloader valve is set to unload at a pressure of 95 pounds, the other may be set to unload at 100 pounds thus enabling the equipment to be unloaded in two steps, and insuring the efficient operation of the same and proper maintenance of the pressure fluid supply.

In Fig. 3 I have shown a circle to make clear the sequence of operation of the pistons in the several cylinders of a twin compound compressor unit. At point 1 we may assume the pistons in one of the compressors to be as shown in Fig. 2, while those in

the other compressor are in a position corresponding to a crank position at 8. This diagram should be followed in connection with the several graphs in Fig. 4, in which the lower dotted lines marked L. P. Cyl. and H. P. Cyl., represent respectively the crank pin effort of the low and of the high pressure compression units of a single compound compressor and wherein the ordinates of the points making up the curves represent in pounds the instantaneous values of the tangential force necessary to rotate the crank as a result of the effect of the compression unit under investigation, while from the abscissæ the momentary crank positions may be observed. The lower solid curve in Fig. 4 is the crank effort diagram of a single complete compound compressor and the upper solid line that of a twin compound compressor with crank pins offset at 45°. From the two solid lines it will be observed that the fluctuation in effort between the maximum and minimum is less for the twin angle compound compressor than for a single angle compound compressor, and also that the total variation from the mean crank pin effort, which is indicated by the top and middle horizontal lines, is reduced, this being evident from a comparison of the sectioned areas at the top and at the middle of Fig. 4.

In the use of my improved construction, it has been found that the difference between the minimum and maximum torque requirement is appreciably less than that resulting from the use of a single angle compound compressor, and that the peaks of maximum torque requirement are equally distributed in such a manner as to produce a relatively smooth crank effort wave and thereby insure long motor and compressor life. It has also been found that by the use of my improved construction it is possible to eliminate entirely the necessity for a heavy fly-wheel, which has heretofore been necessary to absorb the variations in turning effort, thereby reducing the initial cost of the equipment, and removing the subsequent difficulties with friction losses and wear of bearings ordinarily resulting from the use of such a fly-wheel. It is of course also obvious that through the use of my improved construction wherein the two complete compressors are driven by a single motor, one of the compressors may be disconnected from the motor whenever desired through a simple disconnection of its coupling. Attention is also directed to the fact that through my improved arrangement, an installation of large capacity may be provided in an exceedingly small floor space, and that, through the use of a single shaft construction, the necessity for all expensive and power consuming gearing is eliminated.

The placing of the low and high pressure

cylinders as shown in Fig. 3 gives a certain economy in cost of installation and floor space. The intake pipe 10, which is the largest of the pipes shown, is very short and may pass directly through the flooring to an air intake passage, if that construction is desirable. The pipe 11, which is the smaller conductor, is attached to the high pressure cylinder and connects with the distributing system. The longer pipe is, therefore, the smaller pipe and so will require fewer and lighter supports and less floor space. By placing the low compressor cylinder horizontal and the high pressure cylinder vertical and the intercooler between the two, certain marked advantages are obtained in the separation of the oil and water from the gas in the intercooler. As is evident from Fig. 2 the general direction of the flow of the gas is opposite to the direction in which gravity acts. The result is that the liquids condensing in the intercooler tend to fall to the bottom and run into a suitable sump. If the position of the cylinders were reversed the flow of gas would be in general downward and would carry the oil and water which condense in the intercooler to the supply lines.

While I have in this application specifically described one embodiment which my invention may assume in practice, it is to be understood that this form of the same is used for purposes of illustration and that the invention may be modified and embodied in other forms without departing from its spirit, it being my intention to include all such forms within the scope of the appended claims.

What I claim as new and desire to secure by Letters Patent is:—

1. In combination, a pair of compound compressors each comprising angularly disposed high and low pressure cylinders, double acting pistons in said cylinders, and actuating means for said pistons including a single crank operatively connected to both of said pistons, and means for driving said compressors including means for connecting the cranks in angular relation to each other.
2. In combination, a plurality of compound compressors each comprising a double acting high and a double acting low pressure cylinder, said cylinders being arranged at right angles to each other and having the pistons thereof driven by a crank shaft arranged at the intersection of the axial lines of said cylinders and having a single crank operatively connected to the high and low pressure pistons, and means for driving said compressors simultaneously from a common source of power including means for connecting said crank shafts in axial alignment but with the cranks thereon angularly disposed relative to each other.
3. In combination, a plurality of com-

pound compressors each comprising a double acting high and a double acting low pressure cylinder, said cylinders having reciprocating pistons therein, actuating means for the pistons in the cylinders of each of said compressors for causing them to traverse their working cycles in a stepped relation to each other, and means for driving said compressors simultaneously from a common source of power including means for connecting the piston actuating means of the several compressors whereby the pistons in homologous cylinders of said several compressors are at all times either at different points in their paths or reversely moving.

4. In combination, a plurality of double acting angle compressors, and means for driving them in split phase relation.

5. In combination, a plurality of double acting angle compound compressors, and means for successively producing periodic alternate impulses therefrom.

6. In combination, a plurality of independent double acting angle compressors, and means for successively producing periodic alternate impulses therefrom.

7. In combination, a plurality of independent double acting angle compound compressors, and means for successively producing periodic alternate impulses therefrom.

8. In combination, a plurality of compressor units, each having a plurality of pistons moving in angularly disposed paths, and means for driving said units in out of phase relation.

9. In combination, a plurality of compressor units, each having a plurality of double acting pistons, moving in angularly disposed paths, and means for driving said units in split phase relation.

10. In combination, a plurality of double acting angle compressor units having relatively offset crank pins, and means between the same for rotating said crank pins in unison.

11. In combination, a plurality of double acting angle compressors comprising horizontal low pressure cylinders and vertical high pressure cylinders, and means for producing periodic alternate impulses therefrom.

12. In combination, a plurality of angle compressors, and means for selectively driving a single compressor or said compressors together in split phase relation.

13. In combination, a plurality of double acting angle compressors, and means for selectively driving a single compressor or said compressors together in split phase relation.

14. In combination, a plurality of angle compressor units, means for driving the same in split phase relation, and unloading means for said compressor units.

15. In combination, a plurality of angle

- compressor units, means for selectively driving the same singly or together in split phase relation, and unloading means for each of said compressors.
- 5 16. In combination, a plurality of compressors disposed in out of phase relation, and driving means operatively connected thereto including a detachable shaft coupling.
- 10 17. In combination, a plurality of compressors having relatively off-set crank pins, and crank pin driving means therefor including a detachable coupling between one of said pins and the source of power.
- 15 18. In combination, a plurality of independent angle compressor units, a motor, driving means between said elements, and unloading means for said units.
19. In combination, a plurality of independent angle compressor units, a motor, driving means between said elements, and unloading means for said compressor units automatically operable at different pressures.
- 20 21. In combination, a plurality of independent angle compound compressor units, a motor, driving means between said elements, and independently operable unloading means for each of said units.
- 25 22. In combination, a plurality of double acting angle compressors, a motor, driving means between said elements, and independently operable stepped unloading means for said compressors.
- 30 23. In combination, a plurality of angle compressors, a motor, means for driving said compressors therefrom in split phase relation, and means for disconnecting one of said compressors from said motor.
- 45 24. In combination, a plurality of angle compound compressors disposed in out of phase relation, operative connections between the same, and means for driving said operative connections.
- 50 25. In combination, a plurality of independent double acting angle compressors disposed in out of phase relation, operative connections between the same, and means for driving said operative connections.
26. In combination, a plurality of angle compound compressors disposed in split phase relation and having means forming a single shaft, and means for rotating said shaft.
- 60 27. In combination, a plurality of angle compound compressors disposed in split phase relation, means forming a single shaft connected between the same, and a motor connected to said shaft.
28. In combination, a plurality of angle compressors disposed in out of phase relation, means forming a single shaft connected between the same, and a motor for driving said shaft having its armature disposed around the same. 70
29. In combination, a plurality of angle compound compressors disposed in out of phase relation, means forming a single shaft connected between the same, a motor for driving said shaft having its armature disposed around the same, and shaft bearings for said motor disposed between the motor and said compressors. 75
30. In combination, a plurality of angle compound compressors disposed in out of phase relation and each having a shaft, a motor disposed between the same and having an armature shaft, and connections between said armature shaft and said compressor shafts. 80
31. In combination, a plurality of angle compound compressors disposed in out of phase relation and each having a shaft, a driving motor therefor disposed between the same and having its armature shaft disposed 85 co-axially with said shafts, and means for connecting the opposite ends of said armature shaft to said compressor shafts.
32. In combination, a plurality of angle compound compressors disposed in out of phase relation in such a manner that the successive impulses of each compressor alternate with the successive impulses of the other, operative connections between the same, means for driving said compressors, and an unloading means for each of said compressors. 90
33. In combination, a plurality of independent angle compound compressors disposed in out of phase relation in such a manner that the successive impulses of each compressor alternate with the successive impulses of the other, operative connections between the same, means for driving said compressors, and means whereby one of said 105 compressors may be disconnected from said driving means.
34. In combination, a plurality of angle compound compressors disposed in out of phase relation, shafting connecting said compressors, a synchronous motor for rotating said shafting, bearings for said shafting on opposite sides of said motor, means for adjusting said motor between said bearings, an exciter for said motor, and a driving 110 connection between the same and said shafting. 115
- In testimony whereof I affix my signature.
FRED D. HOLDSWORTH.
